[57] CLAIM

The ornamental design for an illuminated ornament, as shown and described.

DESCRIPTION

FIG. 1 is a left front isometric perspective view of the illuminated ornament of the present invention;

FIG. 2 is a front elevational view thereof;

FIG. 3 is a top plan view thereof;

FIG. 4 is a left side elevational view thereof, the right side elevation view being a mirror image;

FIG. 5 is a bottom view thereof; and,

FIG. 6 is a rear elevation view thereof.

The light bulb shown in FIGS. 1 and 2 and the electrical wires shown in FIGS. 1, 2, 4 and 6 are for illustrative purposes only and form no part of the claimed design.
